UNITED STATES PATENT OFFICE.

WILLIAM O. MEISSNER, OF CHICAGO, ILLINOIS.

ANNUNCIATOR-DROP DEVICE.

SPECIFICATION forming part of Letters Patent No. 617,702, dated January 10, 1899.

Application filed July 1, 1896. Serial No. 597,797. (No model.)

To all whom it may concern:

Be it known that I, WILLIAM O. MEISSNER, a citizen of the United States, residing at Chicago, in the county of Cook and State of Illinois, have invented certain new and useful 5 Improvements in Annunciator-Drop Devices, of which the following is a specification.

My invention relates to annunciator-drops, and has for its object to produce a new and 10 improved annunciator-drop, of which the following is a description, reference being had to the accompanying drawings, wherein—

Figure 1 is a plan view of the annunciator-drop and associated parts. Fig. 2 is a side 15 view of the same. Fig. 3 is a front view. Fig. 4 is a section on line 4 4, Fig. 1. Fig. 5 is a view of the surrounding cover for the electromagnet before being bent into shape.

Like letters refer to like parts throughout 20 the several figures.

Referring now to the drawings, the drop proper, A, which drops down so as to expose 25 the plate A', is controlled by means of the electromagnet B. The magnet B is contained within the casing C, which is stamped out of 30 a piece of metal, as shown in Fig. 5, the metal being then bent into shape. The core B' of the electromagnet makes magnetic contact with one part of the case C. A hinged armature C' is connected with the case C and is 35 opposed to the other end of the core of the electromagnet, the casing acting as part of the magnetic circuit. This armature is stamped out of a piece of metal and is provided with 40 the lugs C² C², the armature being held in place by the rod C³, passing through said lugs, said rod also passing through the lugs C⁴ on the case C. An arm D is connected with the armature C' and extends forwardly over the 45 electromagnet, passing through an opening in the plate E. Said arm is provided with a hook E', which normally engages the drop A and holds it in position. Said arm is connected with the armature C' in such a manner

45 that when in its normal position—that is, the position shown in Fig. 2—the armature is held by means of the weight of said arm away from the case C at its lower end, as indicated. The terminals F of the electromagnet project 50 through openings in the armature C', as shown. A pin A² projects beneath the drop A and acts as a stop for said drop. I have

described these several parts in detail, but it is of course evident that this construction may be changed without departing from the 55 spirit of my invention, and I therefore do not wish to be limited to the exact construction herein shown.

The form of the case is such that the spool is protected, being contained therein. This 60 confines the magnetic field of the spool and prevents the magnetic lines of force from threading in the adjacent spools.

The use and operation of my invention are as follows: When the parts are in their normal positions, as shown in Fig. 2, the drop A is held by means of the hook on the arm D and the lower end of the armature C' is held away from the case C. When the circuit is completed through the electromagnet, the 70 lower end of the armature C' is drawn toward the case C and the end of the arm D which engages the drop is raised so as to release said drop. The drop is then carried by gravity to the position shown in dotted lines in Fig. 75 2, the plate A' being exposed to view. When the current ceases flowing through the magnet, the parts take their normal position and the drop A can be moved up to its normal position and is again engaged by the hook E'. 80

It will be seen that I have here a simple and convenient annunciator-drop which can be made at a small cost, the casing acting as part of the magnetic circuit. It will also be noticed that the armature is at the lower end 85 of the magnet and is connected to the drop by means of a projecting arm. The parts are stamped out from sheet metal and may be quickly and cheaply made, and when the parts are put together there is no mechanism 90 which can get out of order, the correct working of the drop being assured.

All of the parts of my annunciator-drop with the exception of the electromagnet are stamped out of sheet metal and then are assembled 95 so as to form a complete device.

I claim—

An annunciator-drop, comprising an electromagnet, a case therefor stamped from a continuous piece of metal, and comprising a 100 body portion provided with wings and adapted when bent into shape to surround the sides and bottom of said magnet, a lug projecting from each side of said body portion near its

end and integral therewith, a projecting part at the other end of said body portion integral therewith and adapted when bent into shape to be connected with the core of the magnet 5 and cover the end of said magnet, an armature pivoted to the lugs on said body portion, a drop located at one end of the magnet, and a hook connected with said armature extending past the magnet so as to engage said drop.

WILLIAM O. MEISSNER.
